(57) **CLAIM**

The ornamental design for a clamp, as shown and described.

DESCRIPTION

FIG. 1 is a front perspective view of a clamp in accordance with our new design;

FIG. 2 is a right side view thereof;

FIG. 3 a left side view thereof for the side opposite that of FIG. 2;

FIG. 4 is a front elevation view thereof;

FIG. 5 is a rear elevation view thereof;

FIG. 6 is a top plan view thereof;

FIG. 7 is a bottom plan thereof; and,

FIG. 8 is a rear perspective view of thereof.

The broken lines shown in the drawings are only provided to illustrate the environment of the design, and form no part of the claimed design.
